FLYING MACHINE

Harry L. Vorse, Portland, Oreg.

Application September 29, 1943, Serial No. 504,283

2 Claims. (Cl. 244—23)

This invention relates generally to aerial transportation and particularly to a flying machine of the heavier-than-air type.

The main object of this invention is the development of a flying machine which will be efficient in operation, inexpensive to manufacture and maintain and easily maneuverable.

The second object is to utilize to the maximum extent the expansive action of the burning gases as a means of propulsion and steering.

The third object is to provide a unique form of skin surface for the streamlined fuselage element.

The fourth object is to achieve vertical take-off and landing, and forward and rearward motion without the use of the conventional wing, rudder, or propeller, as well as to economize fuel, increase flying speed and safety and gain flexibility of operation.

The fifth object is to reduce the amount of head end resistance.

These and other objects are accomplished in the manner set forth in the following specification and as illustrated in the accompanying drawing, in which:

Fig. 1 is a side elevation of the machine with the major portion thereof broken away in vertical longitudinal section.

Fig. 2 is a plan of Fig. 1 with the foremost and rearmost portions thereof broken away in longitudinal horizontal section.

Fig. 3 is a fragmentary perspective view showing the relationship of the power generator to the special airfoil construction.

Fig. 4 is a section taken along line 4—4 in Fig. 3.

Fig. 5 is a front elevation of the machine.

Fig. 6 is a longitudinal section through one of the injectors.

Similar numerals refer to similar parts throughout the several views.

Referring in detail to the drawing, there is shown a streamlined shell 10 having a pointed rearward end 11 and a somewhat blunt forward end 12 around which is mounted a cylindrical shell 13. Disposed within the shell 10 is the transverse floor 14 terminating in the inclined ramp 15 at the lower end of which is formed a head 16 which extends to the upper side 17 of the shell 10 forming a pressure compartment 18. A portion of the upper side 17 over the compartment 18 is stepped as shown in Figs. 3 and 4 so that the riser 19 of each step shall form the discharge of the Venturi tube 20. Directly behind the Venturi tube 20 is formed a depressed channel 21 which communicates by means of the 55

tube 22 with the intermediate point of the Venturi tube 20. Each channel 21 has on its rearward side an inclined surface 23 which merges with the top or tread 24 of the next step.

In the forward end of the shell 10 is disposed a cylindrical power generator 25 to which fuel may be drawn from the tank 26 through a pipe 27 by any convenient means, preferably a pump 28. The purpose of this arrangement is to permit the fuel to be burned directly within the power generator 25, means being provided for selectively energizing the various pumps 28 to vary the rate of burning.

The power generator is connected by various pipes 29 which are diagrammatically shown in solid lines in Fig. 3 and communicate through the head 16 with the compartment 18. Communicating with the power generator 25 is a pipe 30 which extends rearwardly to the three-way valve 30—A having a right hand discharge outlet 31 and a left hand discharge outlet 32 and a rearward discharge outlet 33. The valve 30—A may be operated manually or in any other convenient manner without departing from the spirit of this invention.

In Fig. 6 is shown the amplifiers 34 which are simply injectors drawing air from the open end 35 through the intake openings 36 which are normally held in an open position but are immediately closed by the action of the spring 37 against a valve 38 when the pressure within the amplifier 34 drops for any reason. Obviously, the quantity of gas and air delivered by each amplifier nozzle greatly exceeds the amount of gas supplied by the power generator 25, the ratio of volume being approximately thirty times the original amount of hot gas delivered thereto.

A suitable grille 40 is provided for the opening end 35 and similar closable grilles 41 for the lateral openings 42.

The operation of the device is as follows: When the pump 28 is operated and fuel is drawn from the tank 26 through the pipe 27 and burned within the power generator 25, there is naturally built up a pressure by increase in temperature of the hot gases and this gas is permitted to flow through the pipes 29 through the respective amplifiers 34 where cold air is entrained and the burned gas mixed with air at a correspondingly increased volume is delivered to the compartment 18 from whence it escapes thru the airfoil by way of the aspirators 20 which are flattened Venturi tubes extending transversely to the fuselage and with their flow axis extending longitudinally to the fuselage. The gases now flow from

the aspirators 20 over the various members 24 producing the desired lifting action.

Attention is drawn to the fact that two distinct and yet importantly related results are obtained by this arrangement. First, the zone of reduced pressure is formed above each surface 23 due to the withdrawal of air from the depressed channel 21 through the tube 22 by the action of Venturi tube 20. This definitely increases the lifting effect over each surface 23 while the retarding action of the boundary layer over the surface 23 is greatly reduced by the flow of air from the tube 20. While this is taking place and due to the withdrawal of air from the vestibule 43 within the forward end 12, there is produced an atmospheric unbalance between the front and rear end of the fuselage, thereby urging the aircraft in a forward direction.

It will be further noted that the very element, namely, air or a mixture of air and products of combustion, by means of which the aspirators afford lift to and hold the whole fuselage in aerial suspension, is the selfsame element that, by means of the injectors, indirectly imparts lateral motion to the fuselage.

Attention is drawn to the fact that the lateral openings 42 may be closed or opened by the respective grilles 41 by means of which air is supplied for take-off, landing, and pivoting while lateral motion of the aircraft is not desired and the forward air valve is closed.

In flight or otherwise, air jets are derived from the influx of air into the vestibule, and are used to eliminate air pockets at the tail of the fuselage, and to act as a rudder, all of which are actuated through the valves 30—A at the will of the operator.

It can be seen from the foregoing that while the

drawing has been made somewhat diagrammatically for the purpose of giving a clear understanding of the invention without concealing the principle beneath the mass of details, that there has been provided a radially new and yet novel combination of old and tried elements and phenomena in order to produce a heavier-than-air flying machine having radically different characteristics over any other machine in use at the present time.

10 While I have thus illustrated and described my invention it is not my intention to be limited to the precise form shown herein but I do intend to cover such form and modification thereof as fall fairly within the appended claims:

15 I claim:

1. In a device of the class described, a fuselage surface consisting of a plurality of stepped aspirators, each aspirator consisting of a transversely elongated Venturi tube having its outlet on the step riser, a space between successive steps consisting of a depression directly behind the riser terminating in a convex incline tangent to the following step, connections between each depressed area and the suction side of the Venturi tube and means for supplying gas to said aspirators from the under side thereof.

2. A device of the class described including a streamlined fuselage having a top surface there-

30 of formed of a plurality of steps, the risers of which face the rear of the fuselage, each of said risers having elongated Venturi tubes discharging there-through in a manner that the discharge therefrom shall pass over the next lower riser and means for coupling the low pressure point in the Venturi tube to the low pressure zone disposed at the foot of the step riser.
